ABSTRACT

In a carburetor including a choke valve and a throttle valve, a control mechanism is provided which comprises linking means interconnecting the choke valve and the throttle valve in a manner whereby movement of the choke valve from its open position to its closed position causes the throttle valve to move at a continuously decreasing rate of motion toward its open position.

FIG. 1

FIG. 2

FIG. 3

1
CARBURETOR CONTROL MECHANISM

BACKGROUND OF THE INVENTION

The present invention relates generally to a control mechanism for a carburetor used in vehicles such as automobiles, and more particularly to a choke control device whereby a choke valve is linked with a throttle valve of the carburetor for interdependent movement therebetween. The mechanism of the present invention is particularly suited for use with manual choking devices.

Conventional automobiles do not exhibit optimum performance characteristics during the warming-up phase of their operation. Such engines are designed so that at the time of cold engine idling at normal or low temperatures the choke valve of the engine carburetor is maintained near its closed position to provide a richer fuel and air mixture. Consequently, under such conditions, a relatively large quantity of unburned detrimental CO or HC components will be contained in the engine exhaust gases. Such circumstances are undesirable in view of the fact that they aggravate the problem of air pollution caused by automotive exhaust gases. In order to overcome such problems, efforts are being made to develop engines which exhibit superior warming-up performance wherein engine idling under the conditions described above may be effected with a lean fuel mixture. In such engines it becomes unnecessary to move the choke valve to a substantially closed condition and the engine is able to operate satisfactorily during warm-up without increasing the deleterious components in the exhaust gases.

Thus, it becomes advantageous to provide a choke mechanism whereby the cold engine idling at normal temperatures may be effected without the choke valve being brought to its fully closed condition and with the throttle valve being maintained at an appropriate opening for engine operation, since under such idling conditions the amounts of unburned, detrimental components contained in the exhaust gases may be greatly reduced.

In view of the foregoing, the present invention aims at providing a manually operated choke device which is applicable in an engine exhibiting good warm-up performance, and in which the choke valve may be linked with the throttle valve so that it may be operated in an interrelated manner. By application of the present invention, there may be provided a choke device which can greatly reduce the amounts of unburned, detrimental components contained in exhaust gases during the time of cold engine idling.

SUMMARY OF THE INVENTION

Briefly, the present invention may be described as a control mechanism for a carburetor including a choke valve and a throttle valve each operable to be moved between a closed position and an open position, said control mechanism comprising linkage means interconnecting said throttle valve and said choke valve for interdependent movement thereof, said linkage means being configured to cause the position of the throttle valve to be moved at a relatively lower rate when the choke valve is moved in the region near its closed position, and at a relatively higher rate when the choke valve is moved in the region near its open position.

The choke and throttle valves are interconnected so that as the choke valve is moved from its open position to its closed position, its initial effect upon the throttle valve is to move it toward its open position at a higher rate with the rate of movement of the throttle valve toward the open position decreasing as the choke valve is brought to its closed position.

The various features of novelty which characterize the invention are pointed out with particularity in the 10 claims annexed to and forming a part of this disclosure. For a better understanding of the invention, its operating advantages and specific objects attained by its use, reference should be had to the accompanying drawings and descriptive matter in which there is illustrated and 15 described a preferred embodiment of the invention.

DESCRIPTION OF THE DRAWING

In the drawing:

FIG. 1 is a front view schematically showing an embodiment of a choke mechanism constructed in accordance with the present invention;

FIG. 2 is a diagram illustrating the principles of operation of the structure of the invention; and

FIG. 3 is a graph showing the relationship between 25 the throttle opening and the choke opening in a carburetor constructed in accordance with the invention.

DETAILED DESCRIPTION OF THE PREFERRED EMBODIMENT

30 Referring now to FIG. 1 of the drawing, there is shown a carburetor 1 having a choke valve 2 arranged on the upstream side thereof. The choke valve 2 may be turned from its open position 2a, shown in broken-line form, to its closed position 2b, shown in dot-dash-line form. A throttle valve 3 is arranged on the downstream side of the carburetor 1, with the closed position 3a of the throttle valve 3 being shown in broken-line form. Like the choke valve 2, the throttle valve 3 may be turned from its closed position 3a toward an open position 3c by movement thereof in the direction of an arrow 3b.

The choke valve 2 is connected for rotation with a valve shaft 4 which defines a fixed pivot axis for the choke valve 2. A lever 6 fixedly connected to the valve shaft 4 has attached thereto a choke wire 5 which may be pulled to rotate the lever 6 and the choke valve 2 in the direction of the arrow 2c thereby moving choke valve 2 toward its closed position.

The throttle valve 3 is arranged to rotate with a valve shaft 7 which is fixedly connected to an arm 8. The arm 8 is cooperatively associated with a lever 9 pivotally mounted on the shaft 7 through an intermediary adjustment screw 10 which is used for adjusting the opening of the valve at the time of engine idling while the engine is in a cooled condition.

55 A connecting rod 13 is provided between the lever 6 and the lever 9 with one end of the connecting rod 13 being attached in an aperture 11 of the lever 6 to be freely rotatable therein. The opposite end of the connecting rod 13 is similarly attached in an aperture 12 of the lever 9 and is likewise rotatable relative thereto.

With the arrangement shown, the throttle valve 3 may be operated to be either interdependently linked with the choke valve 2 or to be movable independently thereof. The closing movement of the choke valve 2 in the direction of the arrow 2c causes the opening movement of the throttle valve 3 in the direction of the

arrow 3b, as described above. The opening movement of the throttle valve 3 upon actuation of an accelerator pedal against the force of a return spring, however does not cause the closing movement of the choke valve 2, because the arm 8 fixed on the shaft 7 is turned away from the lever 9.

Referring now to FIG. 2, the points B and B' represent positions of the aperture 11 at which a first joint between the lever 6 and the connecting rod 13 is established. The positions C and C' represent the positions of the aperture 12 at which a second joint is established between the connecting rod 13 and the lever 9. when the choke is fully opened, the aperture 11 occupies position B. When the choke is fully closed, aperture 11 will be in position B'. It will be seen that the aperture 11 may therefore lie on either side of a pair of lines labeled AC and AC' during operation of the device. The line AC extends between a position A, which represents the fixed pivot axis of the choke valve 2 defined by the valve shaft 4, and the point C which represents the position occupied by the aperture 12 when the throttle valve is arranged to define an opening corresponding to the hot engine idling condition. The line AC' connects the position A of the fixed pivot with a position C' which is occupied by the aperture 12 when the throttle valve is at an opening corresponding to cold engine idling.

Let it be assumed that choke valve 2 and the throttle valve 3 are situated such that the former is fully open and the latter is closed so as to enable a hot engine to idle properly at normal temperature. This condition is shown in full line in FIG. 1. Under this condition, if the choke wire 5 is pulled to produce a choking effect, the lever 6 will be pivoted so that the choke valve 2 will be turned toward its closed position. At the same time, the lever 9, the adjustment screw 10, the arm 8 and the throttle valve 3 will all be turned toward a position tending to open the throttle valve 3 through operation of the interconnecting linkage means embodied in the connecting rod 13. The geometrical relationships between the various components of the device are depicted in FIG. 2. It will be seen that with the choke valve 2 in its fully opened position, the included angle between the line AB and the line BC will be smallest. As the lever 6 is swung toward the direction of closing the choke valve 2, this angle will be increased to a maximum of 180° at which time the point B will lie along the line extending between the fixed pivot axis represented by position A and the position of the aperture 12 represented by the position C or C'. As the point B swings past this line to the position B', the angle referred to above will become an external angle greater than 180°.

In the beginning of the pivotal movement of the lever 6 where the opening of the choke valve 2 is still large, i.e. where the choke valve is near its open condition, pivotal movement of the lever 9 will be great so that throttle valve 3 will be moved toward the open condition at a high rate. However, in the region where the opening of the choke valve 2 is rather small, i.e. when the choke valve is near its closed position, the pivotal movement of the lever 9 becomes small so that the throttle valve 3 is turned at a low rate.

The relationship between throttle valve opening and choke valve opening is varied in a manner represented by the solid line of the graph of FIG. 3. When the choke wire 5 is pulled to its full extent so that the choke valve

is fully closed, the throttle valve 3 will occupy the position 3c shown in dot-dash form in FIG. 1. In this position it is slightly opened to suit operation of a cold engine idling at a low temperature.

With reference to FIG. 3 it will be seen that, where a device such as that of the present invention is utilized, the relationship between throttle valve opening and choke valve opening will be in accordance with the solid line appearing in the graph of FIG. 3. The dotted line shown in FIG. 3 depicts the relationship which exists when conventional carburetor mechanisms are used and it will be seen therefrom that the throttle valve opening changes in a proportional relationship relative to choke valve opening. As a result, in the case of a conventional carburetor arrangement, the choke valve will be almost closed, for example as indicated at the point θ_1 , when the throttle valve is at an opening suited for cold engine idling at normal temperature. However, in the case of the carburetor embodying the control mechanism of the present invention, the choke valve will be in a substantially opened condition, as indicated by the point θ_2 shown in FIG. 3, when the throttle valve is at the same position as would produce an opening θ_1 in a conventional carburetor.

Accordingly, it will be seen that a carburetor embodying the control mechanism of the present invention and functioning as indicated above will provide advantageous features in an engine exhibiting good warm-up performance and will greatly reduce the amounts of detrimental components contained in the exhaust gases.

While a specific embodiment of the invention has been shown and described in detail to illustrate the application of the inventive principles, it will be understood that the invention may be embodied otherwise without departing from such principles.

What is claimed is:

1. A control mechanism for a carburetor including a choke valve and a throttle valve each operable to be moved between a closed position and an open position, said control mechanism comprising linkage means connecting said throttle valve with said choke valve to render said throttle valve movable toward its open position in dependence upon movement of said choke valve only when said choke valve moves toward its closed position, said linkage means including means for causing said throttle valve to be moved toward its open position at a relatively lower rate when said choke valve is moved toward its closed position within a region near its closed position and means for causing said throttle valve to be moved toward its open position at a relatively higher rate when said choke valve is moved toward its closed position within a region near its open position.

2. A control mechanism according to claim 1 wherein said choke valve is mounted to rotate about a fixed axis and wherein said linkage mechanism includes a first lever connected to move with said choke valve about said fixed axis, a second lever detachably coupled through a third lever to move with said throttle valve, and a connecting rod extending between said first and second levers, said connecting rod having one end pivotally mounted to said first lever at a first joint and a second end pivotably mounted to said second lever at a second joint, said linkage means being configured such that said first joint may be pivotally moved

to be located on both sides of a line extending between said pivot axis and said second joint.

3. A control mechanism according to claim 2 wherein said linkage mechanism is configured such that during operation of said control mechanism said first joint may be at a position which lies upon said line extending between said pivot axis and said second joint.

4. A control mechanism according to claim 1 wherein as said choke valve moves through a predetermined portion of its movement from its open position to its closed position, said linkage mechanism causes said throttle valve to move in the direction of opening at a continuously decreasing rate of movement.

5. A control mechanism according to claim 1 wherein said linkage mechanism comprises first linkage means affixed with said choke valve to be movable therewith, second linkage means affixed with said throttle valve to be movable therewith, and abutment means located to enable said first and second linkage means to move towards and into abutment with each other when said choke valve moves toward its closed position and away from abutment with each other when said choke valve moves towards its open position, said first linkage means, said second linkage means and said abutment means being interdependently configured to cause said throttle valve to be driven toward its open position by movement of said choke valve toward its

closed position only when said first and second linkage means are in abutment with each other.

6. A control mechanism according to claim 5 wherein said abutment means are adjustable to vary the point of abutment between said first and second linkage means.

7. A control mechanism according to claim 6 wherein said abutment means comprise screw means threadedly engaged with one of said first and second linkage means and extending therefrom for abutment with the other of said first and second linkage means.

8. A control mechanism according to claim 5: wherein said throttle valve is fixedly mounted to a rotatable throttle shaft, and said choke valve is fixedly mounted to a rotatable choke shaft; wherein said first linkage means comprise a first choke-connected lever fixed to said choke shaft, a third choke-connected lever freely rotatably mounted upon said throttle shaft, and a second choke-connected lever pivotally connected to both said first and said third levers and extending therebetween; wherein said second linkage means comprise a throttle-connected lever fixedly mounted to said throttle shaft; and wherein said abutment means comprise means for effecting abutting engagement between said third choke-connected lever and said throttle-connected lever.
